New Inforce 9 Zero Weapon-Mounted Light Recoil Offgrid <https://www.offgridweb.com/gear/new-inforce-9-zero-weapon-mounted-light/> Nov. 19, 2019 (Year: 2019).*

Primary Examiner — Leanne Was-Englehart*(74) Attorney, Agent, or Firm* — Barlow, Josephs & Holmes, Ltd.; Stephen J. Holmes(57) **CLAIM**

The ornamental design for a flashlight, as shown and described.

DESCRIPTION

FIG. 1 is a perspective view of a flashlight in accordance with the present design;

FIG. 2 is another perspective view thereof;

FIG. 3 is still another perspective view thereof;

FIG. 4 is a front view thereof;

FIG. 5 is a rear view thereof;

FIG. 6 is a top view thereof;

FIG. 7 is a bottom view thereof;

FIG. 8 is a right side view thereof; and,

FIG. 9 is a left side view thereof.

The broken lines in the drawings illustrate portions of the flashlight which form no part of the claimed design.
